UNITED STATES PATENT OFFICE

2,634,430

CONVERTIBLE SOFA OR CHAIR BED

James C. Rogers, Lakeland, Fla., assignor of fifty
per cent to John L. Weigand, Lakeland, Fla.

Application March 13, 1950, Serial No. 149,249

6 Claims. (Cl. 5—44)

1

This invention relates to the class of furniture, and more particularly to a chair or sofa adapted to be converted into a bed.

An object of this invention is to provide an article of furniture such as a sofa or chair which is adapted to be converted into a bed when such use is necessary.

A further object of the invention is to provide an article of furniture which is highly attractive in appearance while combining the dual function of a sofa or chair together with the back of a bed so as to enable additional sleeping facilities to be available for use at night, while these sleeping facilities can revert back to the folded embodiment of a chair or sofa for the ornamental and functional use thereof during times when the sleeping facilities are not needed.

A further object of the invention is to provide a convertible sofa or chair bed which has means integrally formed therewith for storing blankets, comforters, and other bed clothes therein in a neat and satisfactory manner.

Yet another object of the invention is to provide a sofa or chair bed which has suitable cushion sections provided with conical springs for insuring cross abutment thereof when they are in juxtaposition with each other.

Still further objects of the invention reside in the provision of this article of furniture which is strong, durable, and efficient in operation, ornamental and attractive in appearance, comparatively easy and inexpensive to manufacture, and which is relatively easy to open.

These, together with various ancillary objects of the invention which will become apparent as the following description proceeds, are attained by this convertible chair or sofa bed, a preferred embodiment of which has been illustrated in the accompanying drawings by way of example only, wherein:

Figure 1 is a top plan view of the invention shown in its extended position with parts thereof being broken away to show other parts in greater detail;

Figure 2 is a side elevational view of the convertible chair or sofa bed, with the various hinged elements being shown in an intermediate stage of folding;

Figure 3 is a side elevational view of the invention shown in position for use as a bed;

Figure 4 is a vertical sectional view of the chair and sofa bed as shown in Figure 3, and taken along the longitudinal axis of the invention;

Figure 5 is a side elevational view of the article of furniture comprising the present invention shown in a folded position;

2

Figure 6 is a vertical sectional view of the invention as taken along the longitudinal axis thereof;

Figure 7 is a partial front elevational view of the convertible sofa or chair back;

Figure 8 is a partial top plan view of the invention in a closed position; and,

Figure 9 is a sectional detail as taken along 9—9 in Figure 4.

10 Continuing reference to the accompanying drawings wherein like reference numerals designate similar parts throughout the various views, reference numeral 10 generally designates the convertible chair or sofa bed comprised in the present invention. This article of furniture has several main portions which are pivotally hinged together.

This article of furniture comprises a base member 12 having a front wall 14, a rear wall 16, spaced side walls 18, and a bottom wall 20 secured together. Attached to the rear wall 16 and extending rearwardly therefrom is a support member 22 on which stop member 24 is secured. The stop member 24 is attached at its other end 25 to a member 26 extending upwardly from the bottom wall 20. Secured to the member 26, the support member 22 on the stop member 24 and extending thereabove is a cover 28 forming a casting 30 in which the back member 32 can be selectively rotated thereto. The back member 32 comprises a head board 34 and a cushion portion 36. The head board is pivotally secured to the rear wall 16 by hinges 38. Secured to the cover 28 is a bracket 40. Terminally secured to the top of the head board 34 and to the bracket 40 is a strip of upholstery fabric 42 to enhance the ornamental appearance of the article of furniture when such is in the extended position by substantially closing the opening through which the head board 34 is rotated into the recess. Further, this strip 42 prevents the entrance of fine articles into the recess so as to relatively insure that the device can be folded to its closed position.

Pivotally attached by hinges 44 to the front wall 14 of the base member 12 is the intermediate member generally designated by reference numeral 46 which comprises a cushion portion 48 of substantially trapezoidal cross section, to which cushion portion there is attached arm rests 50 which are provided for engagement with the side walls 18 when the device is in the closed position. There is provided and attached to the rear wall 16 a support member 52 designed to retain the cushion 48 when the device is in the closed position as shown in Figure 6.

Pivotally secured to the intermediate member

46 by hinges 54 is a seat member generally indicated by reference numeral 56. This seat member comprises a cushion portion 58, a pair of opposed legs 60 and an upholstered front board 62 extending between and secured to the legs 60.

The cushion portions 58 and 36 are provided with inclined sides 64 and 66 respectively to intimately engage the inclined sides 68 and 70 of the cushion portion 48 which is of trapezoidal cross section. All the cushion portions are preferably made from foam rubber or the like and have embedded therein adjacent the inclined sides coil springs such as those indicated at 72 and 74 in the cushion portion 48 and at 76 and 78 in the cushion portions 58 and 36 respectively. The coil springs 72 and 74 are substantially of conical shape and are tapered upwardly. Opposed to these springs 72 and 74 are the springs 76 and 78 of conical shape which are tapered downwardly. Thus, the upper edges of the cushions will be maintained in intimate engagement so as to prevent creases or bumps from being in the bed, thus insuring a sleeper a more comfortable resting position.

Extending from the cushion portion 48 of the intermediate section 46 is a stop member 80 for limiting the position of the cushion portion 36 when the device is in the extended position. To extend this convertible sofa or chair into a bed, it is merely necessary to raise cushion 58 to which the legs 60 are attached tightly and then move this portion forward and away from the back rest cushion 36. This will cause the intermediate section to which the members 48 and 59 are attached to rotate in an arc. By continuing the forward pull on the seat portion 56, while allowing the entire assembly to be lowered, will permit the legs 60 to support the cushion portion 58 and permit the arm rests 50 to support the cushion portion 48. Then, by rotating the back rest cushion portion 36 forward into engagement with the stop members 80 secured to the cushion portion 48, a comfortable bed will be formed.

Since from the foregoing the construction and advantages of this convertible chair or sofa bed are readily apparent, further description is believed to be unnecessary.

However, since numerous modifications will readily occur to those skilled in the art after a consideration of the foregoing specification and the accompanying drawings, it is not intended to limit the invention to the embodiment shown and described, but all suitable modifications and equivalents may be readily resorted to which fall within the scope of the appended claims.

Having described the present invention, what is claimed as new is:

1. An article of furniture comprising a base having a front wall and a rear wall, an intermediate member pivotally attached to said front wall, stop means on said intermediate member, a seat member pivotally attached to said intermediate member, and a back member pivotally attached to said rear wall selectively engaging said stop means, said intermediate member including spaced arm rests secured to a cushion portion, said spaced arm rests comprising means for selectively supporting said intermediate member, said cushion portion being of substantially trapezoidal cross section, said back member abutting an inclined edge of said cushion portion, said cushion portion and said back member being provided with substantially conically shaped coil springs, the springs in said cushion being inverted relative to the springs in said back.

5. An article of furniture comprising a base having a front wall and a rear wall, an intermediate member pivotally attached to said front wall, stop means on said intermediate member, a seat member pivotally attached to said intermediate member, and a back member pivotally attached to said rear wall selectively engaging said stop means, said intermediate member including spaced arm rests secured to a cushion portion, said spaced arm rests comprising means for selectively supporting said intermediate member, said cushion portion being of substantially trapezoidal cross section, said seat member having fixed legs relative to said seat for supporting the free end of said seat member, said seat member abutting an inclined edge of said cushion portion, said cushion portion and said seat member being provided with substantially conically shaped coil springs, the spring in said cushion being inverted relative to the springs in said back.

3. An article of furniture comprising a base having a front wall and a rear wall, an intermediate member pivotally attached to said front wall, stop means on said intermediate member, a seat member pivotally attached to said intermediate member, and a back member pivotally attached to said rear wall selectively engaging said stop means, said intermediate member including spaced arm rests secured to a cushion portion, said spaced arm rests comprising means for selectively supporting said intermediate member, said cushion portion being of substantially trapezoidal cross section, said back member abutting the rear inclined edge of said cushion portion, said cushion portion and said back member being provided with adjacent rows of substantially conically shaped coil springs, said seat member having upholstered leg means for supporting the free end of said seat member, said seat member abutting the forward inclined edge of said cushion portion, said cushion portion and said seat member being provided with adjacent rows of substantially conically shaped coil springs, the springs in said cushion being inverted relative to the springs in said seat and back members.

4. An article of furniture comprising a base having front, rear and spaced side walls, an upstanding arcuate casing extending from said rear wall, a back member pivotally attached to said rear wall and foldable into said casing, a head board secured to said back member and a fabric strip connected between said head board and casing and enclosing the latter.

5. An article of furniture comprising a base having front, rear and spaced side walls, an upstanding arcuate casing extending from said rear wall, a back member pivotally attached to said rear wall and foldable into said casing, a head board secured to said back member and a fabric strip connected between said head board and casing and enclosing the latter, an intermediate member pivotally attached to said front wall and a stop member extending from said intermediate member towards said base, said stop member comprising rear for supporting said back member.

6. An article of furniture comprising a base including upstanding front and rear walls, an intermediate member pivotally attached to said front wall, stop means on said intermediate member, a seat member pivotally attached to said intermediate member, and a back member pivotally attached to said rear wall selectively engaging said stop means, said intermediate member including spaced arm rests secured to a cushion portion, said spaced arm rests comprising means

for selectively supporting said intermediate member, said back member abutting an edge of said cushion portion, said cushion portion and said back member being provided with coil springs.
